UNITED STATES PATENT OFFICE.

JAMES CONTE, OF DESPLAINES, ILLINOIS.

FEEDING MECHANISM.

Application filed February 21, 1921. Serial No. 446,663.

To all whom it may concern:

Be it known that I, JAMES CONTE, a citizen of the United States, residing at Desplaines, in the county of Cook and State of

Illinois, have invented a new and useful Improvement in Feeding Mechanism, of which the following is a specification.

My present invention relates to mechanism of the class shown in my prior Patent No. 1,377,399 dated May 10, 1921, and has for its principal object the organization of the various instrumentalities for initially discharging the articles, their proper disposition and delivery to the grading elements, 10 their receipt from the grading elements, and their delivery to the row-forming mechanism so that the machine as a whole will operate more nearly automatically and will cause much less waste through breakage in- 15 cident to a congestion of the articles in the row-forming mechanism than has heretofore been possible.

More particularly this invention relates to the handling of nut meats that are received 20 from a sorter and grader so that they may be delivered to a coating machine at the desired speed and in substantially uniform and regular order or alinement. In my prior application for Letters Patent of the United 25 States for an improved sorting and grading apparatus, which was filed June 9, 1920, Serial No. 387,550 and issued as Patent No. 1,377,399, I have disclosed an apparatus wherein the articles to be graded and sorted 30 are received from a hopper upon a slowly moving conveyor or apron and from which the articles are discharged upon a plurality of shaker bars (or a "Grisley screen"), so that only the desired articles remain upon 35 the bars to be later discharged from their outer ends. At this point, my present apparatus is adapted to receive the articles discharged from the shaker-bars and distribute 40 them uniformly over a timing conveyor or apron from which they are received upon a second or feed conveyor where the articles are arranged by spaced guide strips to aline 45 them in rows for their delivery to a machine for coating the articles. With my improved 50 mechanism the articles, which may be nuts or the like, are delivered to the coating machine in longitudinal rows through the action of the strips before mentioned, and the two conveyors or aprons regulate the speed 55 of travel of the nut meats so that the feed and delivery of the nut meats will be prop-

erly controlled so as to deliver just the proper quantity to the coater without liability of the nut meats piling up at the 60 coating machine.

Among the divers objects of the present invention are the provision of a feeding mechanism that is capable of controlling the speed at which the articles are fed from the machine; that will handle the articles so that 65 it will not cause injury to them; that will aline the articles in uniform rows prior to delivery; that is comparatively economical to manufacture, and which is novel, compact and durable in construction and dependable 70 in its operation. I prefer to accomplish the divers objects of my invention in substantially the manner hereinafter set forth, and as more particularly pointed out in the 75 claims, reference being had to the accompanying drawings forming a portion of this specification, in which—

Figure 1 is a top plan of the sorting and grading portion of my improved apparatus.

Figure 2 is a similar view of the regulating, alining and feeding portion of said apparatus, and continuing from the left-hand end of Figure 1.

Figure 3 is a longitudinal side elevation of the structure illustrated in Figure 2.

Figure 4 is an enlarged detail in side elevation of the regulating or timing apron and table.

Figure 5 is a transverse vertical section taken on line 5—5, Figure 3, looking in the 90 direction indicated by the arrows.

Figure 6 is a fragmental top plan, enlarged, of the delivery portion of the structure shown in Figure 2.

Figure 7 is a transverse vertical section taken on line 7—7, Figure 2, and slightly enlarged.

Figure 8 is a longitudinal vertical section taken on line 8—8, Figure 6.

Figure 9 is a diagrammatic side elevation 100 of the driving mechanism shown at the top of Figure 1.

Figure 10 is a fragmentary plan of the structure shown in the central portion of Figure 2, slightly enlarged, and portions 105 broken away to disclose underneath parts.

Figure 11 is a longitudinal vertical section taken on line 11—11, Figure 10.

Figure 12 is a fragmentary transverse vertical section of the brush structure or drag 110 employed in connection with the regulating or timing apron.

The structure illustrated in plan in Figure 1 of the drawings is substantially the same as that disclosed in my co-pending application for Letters Patent of the United States filed June 9, 1920, Serial Number 387, 550, and issued as Patent No. 1,377,399, for improvements in a grading and sorting machine, with the exception that the second or lower set of grading bars is omitted for 10 the obvious reason that after the first or top grader has sorted the nut meats so as to retain only the full-size meats, the culls, halves, hulls, etc., that fall through this first grader need no further grading as they 15 are of no use in the present type of machine.

The grading structure shown herein comprises a suitable frame 20 consisting of standards and rails in which the mechanism 20 is mounted and supported, and at the right-hand end of Figure 1 is shown a hopper 21 into which the batch of nut-meats is deposited and which is provided in its bottom with an elongated discharge opening 22, 25 while below this opening travels a slowly moving conveyor belt or apron 23. A brush 24 is mounted in the opening to act as a drag upon the nut meats thereby acting as a distributor and gauge to regulate the quantity of meats deposited upon the apron 23. The apron is mounted upon a flat table 25 which, at its end farthest from the hopper, is provided with a cross-piece 26 that is adjustable longitudinally of the apron to 30 tighten or slacken the same through the medium of set-screws 27 and L-shaped arm 28 that are secured to the ends of the cross-piece. The opposite portion of the apron which is below hopper 21, passes over a 35 driving drum 29, the spindle whereof is journaled in bearings in the side of the supporting frame 20, and is adjusted longitudinally of the machine through the medium of set-screws 30. A worm pinion 31 is mounted upon one end of the drum spindle that is driven by a worm upon a horizontally disposed shaft 32 having a miter gear 33 adjacent its opposite end that derives its motion from a miter gear 34 on 40 a transverse shaft 35 extending across the frame. The shaft 35 is actuated through the medium of a chain and sprocket mechanism 36 that is actuated from the main drive-shaft 37 mounted transversely of the frame and below the end of the table opposite the hopper.

From apron 23 the nut meats are discharged slowly upon a vertical vibratory screen or grader 38 formed of a plurality of longitudinally disposed grading bars mounted in spaced relation upon transverse pieces 39. This grader screen has flared side walls 40 to prevent the shaking off of the nut meats and is given a rapid vibratory 60 movement through the instrumentalities of

any suitable vibrator mechanism actuated by the main drive-shaft 37,—or its associated parts,—for example as shown in my aforementioned co-pending application.

This screen is what is commonly known as a "Grisley screen," and its function is to agitate the nut meats to such an extent that the halves or broken pieces will fall between the bars, together with the hulls and skins and leave only the perfect or selected meats upon the bars from which they are discharged upon an inclined chute 41. This chute 41 has vertical side walls 42, and its upper edge is disposed in a plane slightly below the plane of the lower end of the "Grisley" screen, so that none of the perfect or sorted nut meats will be lost. The chute 41 discharges the nut meats upon an apron 43 that slowly moves towards the coating machine. This apron is mounted upon a table 44, similar in construction to table 25 heretofore alluded to, and at its forward end is provided with an adjustable tensioning bar 45 that slackens or tightens the belt or apron through the instrumentality of the L-shaped brackets 46 that are engaged by the adjusting bolts 47. The opposite portion of the apron passes around a driving drum 48 the spindle whereof is mounted in journal boxes or bearings in T-shaped brackets 49 arising from opposite sides of frame 20 and which are adjusted through the medium of adjusting bolts 50. Extending from chute 41 and forming substantially a continuance of side-walls 42 thereof are the guards 51 that are mounted upon supports 52 secured to the table so as to elevate the lower edge of the guards a slight distance above table 44 in order to permit apron 43 to pass under the same, but it will be understood the space between the apron and the lower edges of these guards is not sufficient to permit any of the nut meats becoming caught therebetween, or being discharged therethrough. This apron 43 is actuated through the medium of a worm pinion 53 upon the spindle of drum 48 that derives its motion from a worm 54 upon the adjacent end of a shaft 55 extending longitudinally of the frame. The opposite end of shaft 55 is connected by a sprocket 56 and chain 57 to a sprocket 58 upon the extended end of shaft 32, as shown in Figures 1 and 9 of the drawings.

Connecting the rear portions of the side walls or guards 51 is a transverse bar 59 that is provided with vertically elongated slots 60 through which bolts 61 pass; said bolts being passed through the block 62 which carries a brush 63 along its lower edge. By moving the brush vertically so that bolts 61 move longitudinally in the slots 60 the position of the brush with respect to apron 43 may be adjusted and then secured by means of a wing-nut 64, as shown 130

in detail in Figure 12. The purpose of this brush is to act as a drag above apron 43 to regulate the quantity of nut meats passing under the brush, and to distribute the 5 same transversely and evenly upon the apron.

It may occur that apron 23 feeds the nuts too rapidly to the sorting or "Grisley" screen 38, in which event the nut meats 10 would become piled upon the mechanism for alining and conveying them to the coating machine, which has heretofore resulted in considerable damage to the nut meats, but by the employment of a speed regulating 15 apron, such as apron 43, and by regulating the quantity and distribution of nut meats upon the apron through the medium of brush 63, I am able to regulate to a nicety the speed and quantity of nut meats fed to the 20 alining mechanism so that the latter will not become congested and break the meats. I have shown no portion of the enrobing or 25 coating apparatus for the reason that this structure forms no portion of my invention, but such apparatus is well known and needs no description here.

From apron 43 the nut meats are discharged upon a feed apron 65 which travels over a table 66 to convey the nut meats to 30 the enrobing or coating apparatus. The apron 65 is driven by a drum 67, the spindle whereof carries upon one end a worm pinion 68 in mesh with a worm 69 mounted upon the adjacent portion of a longitudinally disposed drive-shaft 70. This shaft 70 is synchronized with the driving mechanism of 35 the enrobing or coating apparatus, preferably with the mechanism that conveys the nut meats or articles through said apparatus. It is necessary in the feeding of the 40 nut meats to the enrober or coating apparatus to discharge them onto the receiving structure in longitudinally disposed rows, each nut meat being spaced slightly from 45 the preceding nut meat, and the rows separated a predetermined distance. This I accomplish by means of the structure illustrated in plan in Fig. 2, and the details 50 whereof are shown in Figs. 5 to 11 of the drawings.

Mounted above table 66 and apron 65 is a shaker and row forming mechanism. This comprises a plurality of longitudinally disposed parallel bars 71 connected at their 55 ends by cross pieces 72 so as to form a rectangular shaped frame. The bars 71 are suitably mounted by means of screws, or the like, upon similarly arranged metal straps 73, which, adjacent their ends, are secured by 60 screws or the like to cross-pieces 72, and at the end nearest the enrobing apparatus extend under and beyond cross-piece 72, as seen in Figs. 6 and 8 of the drawings. These metal straps afford a smooth surface to 65 contact apron 65 in its travel over table 66 and

prevent, to a great extent, the unnecessary wear upon the apron. The end of the structure, just described, adjacent the enrobing or coating apparatus, is preferably pivotally connected at one of its corners to table 66 70 through the medium of a pivot pin 74. This pin 74 is inserted in a recess or opening in the table, and for the purpose of adjusting the structure with respect to the enrober apparatus a plurality of openings 75 are made 75 in cross-piece 72. In order that the nut meats may pass readily under bars 72 the latter are formed with notches or recesses 76 which arch over the spaces between the longitudinally disposed bars 71 which 80 readily permits of the passage of the nut meats thereunder.

A suitable inclined guard rail 77 extends along the opposite sides of bars 71 to prevent the shaking off or dislodgment of the nut meats. These guard rails are flared upwardly and outwardly, and at their rear ends are connected by an inclined tray or chute 78 that extends upwardly and under the adjacent end of apron 43 so that the nut meats discharged from said apron will slide down into the spaces upon the apron between bars 71. The lower portion of the tray or chute 78 is provided with a plurality of recesses 79 in order that said chute will fit 95 down between bars 71 so as to insure the nut meats being fed into the spaces between the same.

The cross-piece 72 which is disposed below inclined tray or chute 78 is extended beyond the table a slight distance, as shown in detail in Figure 5, and has a depending extension 80 secured to its under portion. This extension is provided with an elongated slot 81 in which operates an eccentric pin 82 carried upon a disk 83. This disk is mounted upon a short shaft 84 journaled in brackets 85 secured to the underside of table 66, and between these brackets shaft 84 has a grooved pulley 86 secured thereto. A pulley 87 is mounted upon shaft 70 and is connected with pulley 86 by means of a belt 88. Thus, it will be seen that the rotation of shaft 70 causes a rotation of disk 83, and the eccentric pin 82 thereon operating in slot 81 moves cross-piece 105 72 rapidly in a transverse direction across apron 65; the nut meats being slowly deposited upon the inclined tray or chute 78 from apron 43 are shaken transversely upon apron 65 between bars 71 and apron 65 moving toward the enrobing apparatus conveys 110 these nut meats to the latter in longitudinal rows and properly spaced for effective delivery to the enrober.

What I claim is:—

1. In a machine of the kind specified, means for arranging articles handled in substantially parallel rows comprising a longitudinally movable apron, a frame superposed thereon consisting of a plurality of spaced 130

bars arranged substantially parallel to each other, an inclined tray secured to said frame at the receiving end thereof and adapted to discharge the articles upon said apron in spaces between said bars, means for vibrating the receiving end of said frame, a cross-piece secured to said bars adjacent the discharge ends thereof; said cross-piece provided with a plurality of vertical apertures adjacent one end, and a pivotal pin entering one of said apertures to pivot said frame whereby the discharge end of said frame may be adjusted transversely of said apron to regulate the direction of said rows of articles discharging from said apron.

2. A feeding mechanism comprising an apron to receive articles to be fed and move them longitudinally to the end thereof and discharge them therefrom, a drag co-acting with said apron to regulate the distribution of the articles thereon, a second apron in proximity to the discharge end of said first apron, a plurality of spaced longitudinally disposed bars extending over said second apron and vibrated at one end transverse thereto, means for adjusting the opposite ends of said bars transverse to said apron to regulate the direction of discharge of articles from said second apron, and a tray carried by and mov-

able with the vibrated end of said bars to receive the articles from said first apron and deposit them upon said second apron in the spaces between said bars.

3. A feeding mechanism comprising an apron to receive articles to be fed and move them longitudinally to the end thereof and discharge them therefrom, a drag co-acting with said apron to regulate the distribution of the articles thereon, a second apron in proximity to the discharge end of said first apron, said aprons movable in the same direction at different speeds, means for moving said aprons, a plurality of spaced longitudinally disposed bars extending over said second apron and vibrated at one end transverse thereto, means for adjusting the opposite ends of said bars transverse to said apron to regulate the direction of discharge of articles from said second apron, and a tray carried by and movable with the vibrated end of said bars to receive the articles from said first apron and deposit them upon said second apron in the spaces between said bars.

Signed at Chicago, county of Cook and State of Illinois, this 16th day of February, 1921.

JAMES CONTE.
